SEPARABLE BROOCH

Harold L. Pulver, Providence, R. I.

Application March 27, 1937, Serial No. 133,332

7 Claims. (Cl. 63—20)

My present invention relates to brooches, and deals with an improved construction for convertible brooches.

It is the principal object of my invention to provide an improved construction for convertible brooches for facilitating attachment and detachment of separate ornaments to a common base.

It is a further object of my invention to reduce the cost of manufacture and to increase the strength of the parts by utilizing stamped metal which is formed into simple shapes having substantial strength.

With the above and other objects and advantageous features in view, my invention consists of a novel arrangement of parts more fully disclosed in the detached description following, in conjunction with the accompanying drawing, and more specifically defined in the claims appended thereto.

20 In the drawing:

Fig. 1 is a plan view of an assembled brooch; Fig. 2 is a rear view thereof;

Fig. 3 is a perspective view of an ornament showing a support plate arrangement;

25 Fig. 4 is a view of the cooperating base;

Fig. 5 is a section on the line 5—5 of Fig. 2;

Fig. 6 is a perspective view of a separable clamp device;

30 Fig. 7 is a perspective view similar to Fig. 3 and showing a modified construction for the ornament;

Fig. 8 is a perspective view similar to Fig. 4 and showing a modified construction of the base; and

35 Figs. 9 and 10 are perspective views similar to Fig. 3 and Fig. 4 showing further modified constructions.

Referring to the drawing, the novel brooch assembly 10, as illustrated, comprises two separate ornaments 11, 12 which are detachably secured to a common base 13 whereby either ornament may be removed from the base and independently used as a clip, an ornament per se, a buckle, or the like. Each ornament has a support element 14 secured to the back thereof, the preferred construction consisting of a metal plate which may be readily stamped out of sheet stock, and which is soldered or otherwise securely locked to the back of the ornament. The support plate 14 has its outward edge 15 bent upwardly at right angles thereto, this outward edge having spaced openings 16 formed therein, and spaced resilient fingers 17 are preferably struck from the body of the plate and extend upwardly as shown in Fig. 3. The base 13, see Fig. 4, con-

sists of a rectangular plate 18, preferably stamped from sheet metal, having spaced lugs 19 at each end thereof designed to engage the openings 16, and spaced slots 20 positioned as illustrated in Fig. 4, and designed as catch elements for releasable engagement with the fingers 17, the base being also provided with a fastening arrangement 21, such as a pin or the like.

As illustrated in Fig. 5, the base and the ornaments are detachably secured together by positioning the lugs 19 in the openings 16 and then snapping the center part of the base with its catch slots 20 over the resilient latch fingers 17, whereby the parts are releasably held together. To separate the parts, either the ornaments or the base are moved so as to detach the spring fingers 17 from the catch slots 20, the lugs 19 then being readily removable from the openings 16; a clamp device 22 may then be locked into detachable engagement with the plate 14, the clamp device having a bottom plate 23, lugs 24 corresponding to the base lugs 19, slots 25 corresponding to the base slots 20, and a spring clamp 26 which is hingedly mounted to the bottom plate 23, as by means of upstanding hinge ears 27 and a hinge pin 28, a coil spring 29 of standard type being mounted on the hinge pin to maintain the clamp 26 resiliently urged towards the bottom plate 23; the clamp has teeth 30, if desired, for locking engagement with a fabric such as a dress hem.

Instead of using openings 16 such as shown in Fig. 3, and cooperating lugs 19 on the base plate, the support plate and the base may be formed as illustrated in Figs. 7 and 8, the support plate 31 having a socket or recess formed at one end during the stamping operation by an upper wall 32 and one or two side walls 33, and having spaced tongues 34 similar to the tongues 17. In this construction the base 35, see Fig. 4, does not require any end lugs such as 19, but has a plurality of catch slots 36 to cooperate with the tongues 34, the end of the base being inserted in the recess, and the slots 36 engaging the spaced tongues 34.

If preferred, a construction such as illustrated in Figs. 9 and 10 may be utilized, the support plate 37 having an end portion 38 provided with aligning means such as spaced openings 39, spring fingers 40 being formed on the sides or adjacent the sides of the support plate. The base 41, see Fig. 10, is adapted to cooperate with this support plate and has spaced lugs 42 which are insertable in the openings 39, the sides of the base 41 being adapted to snap past the spring fingers 40 for 55

detachable securing of the ornaments to the base. The modified constructions are also provided with separable clamp members similar to the clamp device 22, but formed to correspond with the shapes of the bases as shown in Figs. 8 and 10.

5 While I have described a specific constructional embodiment of my invention, it is obvious that the parts may be made of any material, and that their size, shape and relative positioning may be 10 changed to suit the requirements for different brooch designs, without departing from the spirit and the scope of the invention as defined in the appended claims.

I claim:

15 1. In combination, a base and a plurality of ornaments, said base comprising a sheet metal member having a plurality of lug openings, said ornaments having sheet metal attaching members each with a struck up lug, one end of each attaching member releasably slidably engaging with an end of the base member, said lugs being in register with said lug openings when said ends are in engagement, and said lugs entering said lug openings with a snap action to releasably lock 20 said ornaments to said base, said base having a garment attaching device.

2. In combination, a base and a plurality of ornaments, said base comprising a sheet metal member having a plurality of lug openings and spaced laterally extending lugs at opposite ends, 30 said ornaments having sheet metal attaching members each with a struck up lug, one end of each attaching member releasably slidably engaging with the lugs at the end of the base member, said attaching member lugs being in register with said lug openings when said ends are in engagement, and said attaching member lugs entering said lug openings with a snap action to 35 releasably lock said ornaments to said base, said base having a garment attaching device.

40 3. In combination, a base and a plurality of ornaments, said base comprising a sheet metal member having a plurality of lug openings, said ornaments having sheet metal attaching members 45 each with a struck up lug and an upturned end forming a flange with spaced openings, the flange on each attaching member releasably slidably engaging with an end of the base member, said lugs being in register with said lug openings when said end and flange are in engagement, said lugs entering said lug openings with a snap action to 50 releasably lock said ornaments to said base, and said base having a garment attaching device.

4. In combination, a base and a plurality of

ornaments, said base comprising a sheet metal member having a plurality of lug openings and spaced laterally extending lugs at opposite ends, 5 said ornaments having sheet metal attaching members each with a struck up lug and an upturned end forming a flange with spaced openings, the flange on each attaching member releasably slidably engaging with the lugs at an end of the base member, said struck up lugs being in register with said lug openings when said end and flange are in engagement, said lugs entering said lug openings with a snap action to releasably lock 10 said ornaments to said base, and said base having a garment attaching device.

5. In combination, a base and a plurality of 15 ornaments, said base comprising a sheet metal member having a plurality of lug openings, said ornaments having sheet metal attaching members each with a struck up lug and with a socket at one end, the socket of each attaching member 20 releasably slidably engaging with an end of the base member, said lugs being in register with said lug openings when said socket and end are in engagement, said lugs entering said lug openings with a snap action to 25 releasably lock said ornaments to said base, and said base having a garment attaching device.

6. In combination, a base and a plurality of ornaments, said base comprising a sheet metal member having a plurality of lug openings, said 30 ornaments having sheet metal attaching members each with a struck up lug and with a socket at one end, said socket comprising an integral end wall having an integral reentrantly bent portion 35 extending parallel to the attaching member and integral said flaps, the socket of each attaching member releasably slidably engaging with an end of the base member, said lugs being in register with said lug openings when said socket and end are in engagement, said lugs entering said lug 40 openings with a snap action to releasably lock said ornaments to said base, and said base having a garment attaching device.

7. In combination, a base and a plurality of 45 ornaments, said base comprising a sheet metal member, said ornaments having sheet metal attaching members having spaced lugs, one end of each attaching member releasably slidably engaging with an end of the base member, said base member releasably locking with said lugs with a snap action when said ends are in engagement, 50 and said base having a garment attaching device.

HAROLD L. PULVER.
